UNITED STATES PATENT OFFICE.

FREDERICK LAMBERT, OF MINNEAPOLIS, MINNESOTA.

DESIGN FOR A COMBINATION TRAFFIC SIGNAL AND SIGNPOST.

Application filed July 7, 1924. Serial No. 10,078. Term of patent 14 years.

To all whom it may concern:

Be it known that I, FREDERICK LAMBERT, a citizen of the United States, residing at Minneapolis, in the county of Hennepin and State of Minnesota, have invented a new, original, and ornamental Design for Combination Traffic Signals and Signposts, of which the following is a specification, reference being had to the accompanying drawing, forming part thereof.

The figure is a perspective view of a combination traffic signal and signpost of my design.

I claim:

The ornamental design for a combination traffic signal and signpost, as shown.

FREDERICK LAMBERT.
